UNITED STATES PATENT OFFICE.

CHARLES L. SHELDON, OF AUBURN, NEW YORK.

AXLE.

SPECIFICATION forming part of Letters Patent No. 470,261, dated March 8, 1892.

Application filed January 9, 1892. Serial No. 417,530. (No model.)

To all whom it may concern:

Be it known that I, CHARLES L. SHELDON, a citizen of the United States, residing at Auburn, in the county of Cayuga and State of 5 New York, have invented certain new and useful Improvements in Axles, of which the following is a specification.

My invention relates to axles for vehicles; and it consists, first, of an axle or axle-blank 10 formed of a continuous bar and rounded at the lower edges for parts or the whole of its length, and, secondly, in the means of forming such axles or axle-blanks, fully set forth hereinafter, and illustrated in the accompanying 15 drawings, in which—

Figure 1 is a perspective view of an axle bar or blank, showing my improvement, one end of the bar being cut away to illustrate the cross-section. Fig. 2 is a section on the line 20 2 2, Fig. 1, enlarged. Fig. 3 is a perspective view illustrating my invention as applied to a bar of uniform dimensions. Fig. 4 is a sectional view illustrating a pair of rolling-dies for forming the bar. Fig. 5 is a sectional 25 view illustrating a pair of pressing-dies for forming the bar.

The bar from which the axle or axle-blank is to be made may be of any suitable form. Thus it may be a straight bar of uniform 30 dimensions in cross-section—for instance, a seven-eighths-inch bar—or it may be a bar that has previously been reduced in width in the center and spread. In any case, however, the bar must be of such length as to 35 form a continuous solid axle in one piece and with end portions that are formed or may be formed into the ordinary conical journals and intermediate portions which are upset in any suitable manner or otherwise formed so as to 40 make the ordinary collars. In cases where it is desired to reduce and spread the bar toward the center this reduction and spreading may be effected in the operations required to 45 round the edges.

In the construction shown in Fig. 1 the lower edges of a bar that has been formed into an axle-blank are indented or rounded at intervals, so as to form the spots α and intermediate rectangular portions γ , having the 50 cross-sectional form indicated in the enlarged section, Fig. 2, and adapted to receive the clips. In the construction shown in Fig. 3

the axle or blank is of uniform dimensions in cross-section throughout its length between the collars 2 2 and is indented or chamfered 55 at intervals to form spots α and intermediate rectangular portions γ . Whatever may be the general form and dimensions of the bar itself, the axle or axle-blank as formed consists of a continuous piece having the journals, the collars, and the intermediate portion integral throughout and free from welds, so as to preserve the original strength of the bar. 60

In rounding the edges at intervals to form the spots upon the bar I prefer to make use 65 of dies D D', which may be revolving dies, as illustrated in Fig. 4, or pressing-dies, as illustrated in Fig. 5, although other means may be employed. In either case the dies have suitable grooves or faces to receive between 70 them the bar that is to be operated upon, and one of the grooves in one of the dies is provided with projections 3 or is rounded at the corner, so that as the bar is submitted to pressure between the dies the edges at one side of 75 the bar will be rounded at intervals to form the spots α , leaving the intermediate rectangular portion γ .

When revolving or rocking dies are employed, the projections 3 are in one of the 80 grooves of one of the rolls, and, if desired, the said grooves may be so formed that when a flat bar is introduced between the rolls and passed between them by the rotation or rocking of the rolls the bar will be flattened and 85 shaped as may be required to make an axle of any desired form and construction and proportions.

In case it is desired to form the axle or axle-blank with the lower edges rounded throughout their length, or to leave square portions ν only adjacent to the shoulders, the grooves of the dies are correspondingly formed. Whether the axle or axle-blank has the lower 90 edges rounded for a part or the whole of the length a much more symmetrical form and finished appearance is secured.

Without limiting myself to the precise construction or form or proportion of axle shown or to the specific devices for forming the same 100 or rounding the edges, I claim as my invention—

1. An axle bar or blank consisting of a continuous bar of metal spread toward the cen-

ter and with the lower edges rounded for a part or the whole of their length, substantially as described.

2. An axle bar or blank consisting of a continuous bar of metal having journals and collars spread at the center and provided at the lower edges with a series of indentations or chamfers x , substantially as set forth.

3. The within-described improvement in 10 the manufacture of axles, the same consisting in subjecting a continuous bar to the action of dies, one or more of which has a series of projections 3 arranged to indent or chamfer opposite edges of the bar at one side to form 15 spots or recesses x , separated by intermediate rectangular portions y , and then upsetting

the bar near each end to form collars 2, substantially as set forth.

4. In the manufacture of axles, subjecting a bar to the action of dies having grooves 20 constructed and arranged to flatten the bar and spread it toward the center and with projections 3 arranged to chamfer and indent opposite edges of the bar at one side, substantially as set forth.

In testimony whereof I have signed my name to this specification in the presence of two subscribing witnesses.

CHARLES L. SHELDON.
